UNITED STATES PATENT OFFICE

CHARLES McLELLAN, OF SIOUX CITY, IOWA

ROTARY TOOTHBRUSH

Application filed July 13, 1929. Serial No. 377,996.

My invention relates to rotary toothbrushes and has for its object to provide a toothbrush of simple, durable and inexpensive construction.

5 The invention is embodied in a device having a casing providing a hood for covering a portion of the brush and a handle to be grasped by the hand of the operator, a brush journalled in the handle and a knob to be engaged by the fingers of the operator for rotating the brush.

As already stated, it is my purpose to provide a construction as inexpensive as possible. However, another feature is a very important 15 element in a brush of this character, namely, the possibility of removing and replacing the brush per se from the casing which holds it. To this end, my invention contemplates providing a device in which the brush is embodied in a detachable unit comprising the brush and a shank by means of which the brush may be attached to the knob.

20 A further object of my invention necessarily resulting from the above mentioned object is that of providing an arrangement in which the brush and knob may be attached together in connection with the handle which supports them in such a way that they are journalled within the handle for rotation. At the same time, it is my purpose to provide 25 an arrangement in which the attaching or detaching of the brush may be accomplished in a very simple manner.

30 To this end, my invention contemplates the use of a snap link driving connection between the brush and the knob and the hiding of said driving connection within the handle of the brush.

35 A further object is to provide a device of the above character in which the snap driving connection between the two rotating elements of the brush is not required to sustain the burden of supporting the brush and knob in axial alignment with each other. To this 40 end, my invention proposes to utilize the han-

dle as a bushing to support rotatable shaft portions of the brush and knob, respectively, the shaft portions both being of sufficient length to give the required support and the snap driving connection being interposed 50 therebetween and positioned intermediate the ends of the handle.

Another object of my invention is to provide a brush which is particularly adapted to be cleaned and kept in a sanitary condition. 55

With these and other objects in view, my invention consists in the construction, arrangement and combination of the various parts of my device, whereby the objects contemplated are attained, as hereinafter more 60 fully set forth, pointed out in my claims, and illustrated in the accompanying drawings, in which:

Fig. 1 is a side elevation of a brush embodying my invention. 65

Fig. 2 is a longitudinal, sectional view of the brush.

Fig. 3 is a similar sectional view of the rotating assembly, the brush being omitted and parts being shown in elevation to further 70 illustrate the construction.

Fig. 4 is an end view of the brush shank.

Fig. 5 is an end view of the brush shank viewed from the socket end.

Fig. 6 is an end view of the knob viewed 75 from its shaft end.

Fig. 7 is an end view of the assembled brush and

Fig. 8 is a detail, sectional view showing a 80 modified form of snap link connection.

I have used the reference character 10 to indicate generally the casing of the device which is constructed in one integral piece to form a hood 11 and a handle or barrel 12. 85 The barrel is provided with an axial bore, which is sufficiently smooth to form a bearing surface for the rotating parts. Between the hood 11 and barrel 12 is formed a squared shoulder 13, which may be considered as one 90

end of the barrel 12, the other end also being squared as shown.

The brush unit comprises a cylindrical brush 14, which is provided with the central core or spindle 15, on which the bristles of the brush are mounted. The spindle 15 projects from one end as at 16, where it is received in the shank 17 of the brush, which is cylindrical in form and sized to fit smoothly within the bore of the barrel 12.

The shank 17 is provided at one end with an enlarged collar 18, formed integrally with the shank and adapted to engage the shoulder 13 of the barrel 12.

At its other end the shank 17 is provided with a socket 18^a, which is preferably polyhedral in construction, as shown in Fig. 5. The end of the shank 17 is split as at 19 to form two socket jaws 20, the slot 19 allowing the jaws to spread.

The jaws 20 are also cut away as at 21 so that the cross sectioned area within the circumference of the outer edges of the jaws is less than the cross sectional area of the interior of the barrel 12. The object of thus reducing the jaws is to allow them to spread within the barrel 12.

The knob 22 is formed integrally with a knob shaft 23, which also is shaped to smoothly fit within the bore of the barrel 12. A shoulder 24 is formed between the shaft 23 and knob 22, which engages the free end of the barrel 12.

The end of the shaft 23 opposite the knob 22 is provided with a teat 25, which is shaped to fit snugly within the socket 18. The socket 18^a and teat 25 are formed with one or more inclined sides, thus enlarging their cross sectional area near the inner extremity of the socket and near the end of the teat.

The teat is provided with a bevelled end face 27, which spreads the jaws 20 to allow the teat to enter the socket.

It will now be seen that a snap construction is provided, which not only acts as a driving connection between the two rotatable members, but also serves to hold them together against pulling apart. At the same time, when sufficient pull is exerted against the members by the hands of the operator, they may be separated for the purpose of replacing a brush or for cleaning.

It will be understood that the ordinary person using a brush of this kind will wish to clean the brush, at least to rinse it, after each period of use. For this purpose, it will be desirable to separate the parts and to wash or rinse them individually. Thus the brush is much more sanitary than it would be if the parts were not readily separable.

The shaft 23 and shank 17 are journaled within the barrel 12 so that lateral support for the brush and knob are provided. The snap connection is thus relieved of all lateral strains and may thus be constructed more

delicately and with much less length to the socket than would otherwise be necessary. The only functions of the snap connection are those of providing a driving connection and yieldably holding the knob and brush together.

The shoulders 18 and 24 tend to prevent the entrance of moisture or foreign material into the barrel of the brush and thus assure smooth operation of the brush.

It will be understood that the snap construction might be any of several types. For instance, the construction shown in Fig. 8 might be employed, wherein, instead of a teat that is approximately square in cross section, a flat finger 30 may be employed, adapted to enter a slot 31 in the end of the shank 17 and provided with a pair of lugs or the like 32, adapted to enter depressions formed for them between the jaws 20^a.

The advantages of my invention reside in its sanitary features and in its simplicity and inexpensiveness. The combination of the sanitary feature, the detachability of the brush unit and the simplicity and sturdiness of construction are believed to be novel in rotary toothbrushes.

Some changes may be made in the construction and arrangement of the parts of my invention without departing from the real spirit and purpose of my invention, and it is my intention to cover by my claims, any modified forms of structure or use of mechanical equivalents, which may be reasonably included within their scope.

I claim as my invention:

1. In a rotary tooth brush, a barrel serving as a handle, said barrel having a longitudinal cylindrical bore extending therethrough, a brush, a shank in which said brush is mounted, a driving member including a shaft and a knob, the shank and shaft having cylindrical portions snugly journaled in the barrel, and a separable connection between the cylindrical portions, comprising projections on the ends of the respective cylindrical portions extending longitudinally thereof into latching engagement, the projections having non-cylindrical faces in engagement with each other to form a driving connection between the cylindrical portions, said projections being of resilient material and the said faces being inclined laterally outward from the cylindrical portions, so that the projections must spring apart in order to move past each other from latched to unlatched positions.

2. In a rotary tooth brush, a barrel serving as a handle, said barrel having a longitudinal cylindrical bore extending therethrough, a brush, a shank in which said brush is mounted, a driving member including a shaft and a knob, the shaft and shank being of resilient material and having cylindrical portions journaled in the barrel, the inner end of one

of said cylindrical portions being split to form two separated members provided with a space between them that is non-cylindrical in cross-section and has a constricted mouth, 5 and a teat formed on the other cylindrical portion, including an enlarged portion joined to the body of said other cylindrical portion by means of a reduced neck and receivable between said spaced members to form there- 10 with a driving connection between the shank and shaft and to latch them together against pulling apart under normal working conditions.

Signed this 8th day of July, 1929, in the
15 county of Woodbury and State of Iowa.

CHARLES McLELLAN.
